DRILL STEEL RETAINING DEVICE

Original Filed Feb. 16, 1925

FIG. 1

FIG. 2

INVENTOR.
CHARLES A. HULTQUIST
BY *AB Bowman*
ATTORNEY

UNITED STATES PATENT OFFICE

CHARLES A. HULTQUIST, OF LOS ANGELES, CALIFORNIA, ASSIGNOR TO INDEPENDENT PNEUMATIC TOOL COMPANY, OF CHICAGO, ILLINOIS, A CORPORATION OF DELAWARE

DRILL-STEEL-RETAINING DEVICE

Original application filed February 16, 1925, Serial No. 9,480. Divided and this application filed January 12, 1927. Serial No. 160,641.

My invention relates to a drill-steel retaining device for drilling machines, and is a divisional application of the subject matter of my previous application for drill-steel retaining devices, filed in the United States Patent Office, February 16th, 1925, under Serial No. 9,480, patented May 20, 1930, No. 1,758,949.

The objects of this invention are; first, to provide a particularly simple, economical, durable, and efficient device for preventing the drill steel of drilling machines from becoming detached from the chuck of the machine in which it is loosely seated, and one which can be readily thrown into and out of steel retaining position; second, to provide a device of this class which is pivotally mounted at the side of the barrel of the drilling machine and which may be positively locked in a drill-steel retaining position, and which may still be shifted a considerable distance about its pivotal axis so as to reduce to a minimum the danger of the retainer flying back to the steel retaining position and injuring the hands or fingers of the operator; third, to provide a device of this class which will remain in a positive locked retaining position even though the drill steel is forced with its abutment against the same; and, fourth, to provide, as a whole, a novelly constructed device of this class and one which will not readily deteriorate or get out of order.

With these and other objects in view as will appear hereinafter, my invention consists of certain novel features of construction, combination and arrangement of parts and portions, as will be hereinafter described in detail and particularly set forth in the appended claims, reference being had to the accompanying drawings and to the characters of reference thereon which form a part of this application in which:

Figure 1 is a side elevational view of a conventional drilling machine with my drill-steel retaining device mounted thereon and shown in a steel retaining position thereon, a drill steel being shown in the barrel of the machine; and Fig. 2 is an enlarged fragmentary side elevational view thereof taken at 2-2 of Fig. 1, showing particularly my drill-steel retaining device, the device being shown

by dotted lines in an angular or out-of-the-way position for removing the drill steel.

Like characters of reference refer to similar parts and portions throughout the views of the drawings.

The drilling machine, indicated by the character 1 in the drawings, may be of any suitable construction, the type shown being employed for drilling down holes, but, it will be understood, that the invention can be used with other types of drilling machines. The drilling machine is provided at its lower end with a barrel 2 in which is inserted the one end of a drill steel 3 which is provided with a shoulder, or abutment, 4 spaced from the end of the drill steel inserted in the barrel. The drill steel 3 is permitted to slide in and out of the barrel 2 readily, when the retaining device, to be described hereinafter, is not in such position as to prevent such movement of the drill steel.

The retainer, or retaining device, indicated by R, is generally U-shaped and pivoted with its legs, indicated by 6, at the opposite sides of the barrel 2. At the cross, or connecting portion of the arms or legs 6 of the U-shaped retainer, is a transversely extending semi-circular, or U-shaped abutment 5. Said abutment 5 partly surrounds the drill steel, when the retainer is in a downward or retaining position, and is adapted to be engaged by the outer face of the abutment, or shoulder 4 during the drilling operation, to retain the drill steel in the barrel. The ends of the legs of the semi-circular, or U-shaped abutment 5 are provided with upwardly extending lugs 5a to positively prevent the retainer from being shifted out of the way when the drill steel is inserted into the barrel with its shoulder, or abutment, 4 against the abutment 5.

The legs 6 are bifurcated, or forked, intermediate their ends, the planes extending through the furcations of each leg being perpendicular to the plane extending through the two legs 6. The inner ends of the bifurcated portions, or forks, of said legs provide semi-circular bearings 6a which are positioned against and around the under sides of studs 7 projecting laterally from the sides of the barrel 2 and positioned in alignment with the

axis thereof. The furcations 6b of the retainer are in the form of bolts and serve as guides. On the furcations of each leg is slidably mounted a bearing plate 8 which is normally positioned against the upper side of the stud 7 in opposed relation to the bearing portion 6a. At the outer ends of the furcations of each leg is mounted a spring retaining plate 9 which is held in position on said furcations by nuts 10 screwed on to the outer ends of the furcations. Between the plates 8 and 9, and between the furcations 6b of each leg, is positioned a compression spring 11 which is retained in position between said plates by lugs 8a and 9a extending toward each other from the plates 8 and 9, respectively.

The upper side of one, or both, of the studs 7 is provided with a longitudinal, substantially semi-circular depression 7a into which extends, when the retainer is in a steel retaining position, a correspondingly shaped projection, or ear, 8b which extends downwardly from the middle portion of a circular depression 8c into which the upper side of the pivot portion, or stud, 7 normally extends. Thus the retainer, or retaining device, is locked relative to the pivot means by the interlocking means of the studs 7 and the plates 8 against movement unless considerable force is brought to bear against the lower end of the retainer and only when the abutment 4 is clear of the lugs 5a.

The mounting of the retainer on the studs in the manner described, permits the retainer to be shifted more than ninety degrees about its pivotal axis and thus reduces to a minimum the danger of the retainer slipping back to its retaining position and pinching or crushing the hands or fingers of the operator.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. The combination with the barrel of a drilling machine, and a drill steel in the barrel, of a pivot means extending to the side of said barrel, a drill-steel retainer having a portion at the end of said barrel engageable by an abutment on said drill steel and having means extending to the side of said barrel, said means having a bifurcated portion straddling said pivot means and having a pivot bearing at the inner end of said bifurcated portion engaging the rounded underside of the pivot means, a bearing mem-

ber slidably mounted on the furcations of the bifurcated portion and engaging the upper side of said pivot means, said bearing member and pivot means having portions adapted to hold the retainer in a drill-steel retaining position, a spring retaining plate slidably mounted on and between said furcations, nuts at the outer ends of said furcations for holding said spring retaining plate in position, and a compression spring positioned between said slideable bearing and said plate, and between said furcations.

2. The combination with the barrel of a drilling machine, and a drill steel in the barrel, of studs projecting laterally from the barrel, of a U-shaped drill-steel retainer, the legs thereof having forked portions forming, at their inner ends, bearings engaging the undersides of the studs, the connecting portion of the legs of the U-shaped member being engageable by an abutment on said drill steel, bearings slidably mounted on the furcations of said forked portions, said bearings and said studs having portions adapted to hold the retainer in a drill-steel retaining position, spring retaining plates slidably mounted on and between said furcations, nuts at the outer ends of said furcations for holding said spring retaining plates in position, and compression springs positioned between said slideable bearings and said plates, and between the furcations of each fork.

3. The combination with a barrel of a drilling machine and a drill steel in the barrel, of a pivot means extending to the side of said barrel, a drill-steel retainer having a portion at the end of said barrel engageable by an abutment on said drill steel and having means extending to the side of said barrel, said means comprising a bifurcated portion straddling said pivot means and having a pivot bearing at the inner end of the bifurcated portion, said pivot bearing engaging the rounded under side of the pivot means, a bearing member extending over and around and slidably mounted on the furcations of the bifurcated portion and engaging the upper side of said pivot means, said bearing member and pivot means having portions adapted to hold the retainer in a drill-steel retaining position, a spring retaining plate slidably mounted on, around, over and between the furcations, means at the outer ends of the furcations for holding the spring retaining plate in position thereon, and a compression spring positioned between said slideable bearing and said plate.

In testimony whereof, I have hereunto set my hand at Los Angeles, California, this 3rd day of January, 1927.

CHARLES A. HULTQUIST.
